UNITED STATES PATENT OFFICE.

GEORGE H. BAILEY, OF PITTSBURG, PENNSYLVANIA.

TANK FOR WATER-CLOSETS, &c.

940,951.

Specification of Letters Patent. Patented Nov. 23, 1909.

Application filed November 16, 1908. Serial No. 462,855.

To all whom it may concern:

Be it known that I, GEORGE H. BAILEY, a resident of Pittsburgh, in the county of Allegheny and State of Pennsylvania, have invented a new and useful Improvement in 5 Tanks for Water-Closets, &c., of which the following is a specification.

This invention relates to flushing and like tanks and more particularly to flushing 10 tanks for water closets and the like.

The object of the invention is to provide a tank for this purpose constructed of sheet metal and in which dripping and other objectionable features due to sweating is overcome.

Sheet metal flushing tanks covered with enamel have been proposed. Such tanks are sanitary and sightly but are subject to sweating and objectionable on that account. At 15 attempts have heretofore been made to overcome this objectionable feature by means of what amounts to a double tank, that is, one tank within another.

The present invention aims to secure a 20 tank in which the sweating feature is largely, if not entirely, overcome and by a construction which is simple and cheap to manufacture.

The invention comprises the construction 25 and arrangement of parts hereinafter described and claimed.

In the accompanying drawing Figure 1 is a perspective view of my improved tank with the cover removed; Fig. 2 is a vertical transverse section through the same with the cover in place; Fig. 3 is a vertical longitudinal section through the same showing modified means for holding the cover in 35 place; Fig. 4 is in part a plan view, and in part a horizontal section through the same; Fig. 5 is a perspective view of the outer front sheet; and Fig. 6 is a detail view of a modification of the means for fastening the cover.

The tank is provided with a rear wall 1 and bottom 2 of single thickness and preferably formed from single sheet of metal bent to angle shape, and with an outer combined front and end wall 3, and an inner combined 40 end and front wall 4. The walls 3 and 4 are each formed of a single sheet of metal bent to form the front and end wall portions with rounded corners as shown. These are joined to the rear wall and bottom by any suitable 45 means, but preferably by welding so as to provide a joint of not materially greater

thickness than the sheets themselves. In order to reduce to a minimum the amount of welding or other joining to be done the sheets are so shaped that a single joint will 50 unite all three of the sheets forming the tank. To this end the outer front and end sheet 3 has its bottom edge turned or flanged inwardly as at 5, and the vertical edges of the end wall portions also flanged inwardly 55 as at 6, the flanges 5 and 6 in width being equal to the space 7 between the inner and outer walls. This brings the edges of the outer sheet into contact with the edges of the inner sheet both at the bottom and at 60 the back, and the rear wall and bottom are cut to fit against these meeting edges of the sheets 3 and 4. Consequently, a single welded, brazed or soldered joint unites all three 65 sheets, there being formed the two vertical 70 joints 8 at the rear and the horizontal joint 9 at the bottom. The preferred form of uniting these sheets is by either the electric welding or blow pipe process.

The joints 8 and 9 are inward from the 75 outer exposed surfaces of the tank so that they are invisible and therefore do not mar the appearance of the tank. Furthermore, the joints are formed in flat surfaces and not on the corners, which is of importance as it 80 not only is easier to make the weld but also prevents the enamel from running off when enameling. The joints are somewhat thicker 85 than the other parts of the sheet and in enameling hold the heat somewhat longer. 90 When the weld is made on corners or angles the enamel is likely to run off before the metal cools sufficiently to hold it. This is overcome by forming the weld inwardly 95 from the corners in flat surfaces. This feature is applicable to all forms of sheet 100 metal tanks whether having double or single walls and the claims will be understood not to be limited to double walled tanks except where so specified. The rear wall and bottom 105 formed from a single sheet is also applicable to a tank without double walls and the claims including this feature are intended to include single walled as well as double walled tanks except where the double walls are specifically included.

The outer sheet 3 at its bottom may be provided with the bead or swell 10 to enhance the appearance and at its top with the bead or swell 11 for strengthening the same. 110 The inner sheet 4 is also beaded at its upper edge as at 12, and is also provided with one

or more corrugations 13 to give strength. The rear wall is likewise beaded at its top, as shown at 14.

The tank is closed by a cover 15, also of sheet metal pressed to shape and enameled. Said cover may be held in place by various means. Fig. 2 shows it held in place by means of cap nuts 16 on small threaded rods 17 adapted to project through holes in the cover and being threaded into angle plates 18 held by the screws or other members 19, used for securing the tank to the wall or other base. Fig. 6 shows the rod 17 provided with a loop or eye 20 through which the screw 19 passes. The arrangement of Fig. 2 is preferred, as it enables the rod 17 to be adjusted vertically and provide just enough projection to receive the nut 16 and enable the cover to be tightly clamped. Fig. 3 shows the ends of the cover curled over to underlie the beads 11 of the end walls of the tank as shown at 21. This cover is slipped on from the front and requires no other fastening means.

The body of the tank described is composed of only three sheets, namely, the rear wall and bottom sheet and the inner and outer front and end forming sheets, and these three sheets are united by a single joint thus reducing to a minimum the amount of welding or other labor necessary to unite the sheets. The tank after being formed is coated with enamel, at least on its exterior surface and has the interior surface and the space between the inner and outer walls either enameled, galvanized or covered with paint or other substances to prevent corrosion. The tank is provided with the usual inlets and outlets and flushing mechanism of any suitable character.

In the manufacture of the tank the sheets forming the same will be bent to shape and strained beyond their elastic limits, so that there will be no tendency of the metal to move and crack the enamel. The rounded corners and the bead at the bottom provide a surface which readily takes the enamel and with little danger of the same cracking off.

The double front and end walls provide an air space which prevents sweating on the front and end portions of the tank, and since the rear wall is usually placed in close contact with the wall of the room or other base, there is little or no opportunity for sweating at this point, and the restricted area at the bottom produces such a small amount of sweating that it is not objectionable. It is, however, covered with a mat 22 of waterproof felt or other fibrous material which acts as a heat insulator and prevents sweating. The tank is therefore practically free from objection on account of the sweating.

In order to remove the water of condensation in the space 7, said space is connected by a drain tube 24 with the flushing fitting

25. In flushing water may back through the drain tube into the space 7, but this will do no harm as it will again run out as soon as the flushing valve closes. The end of the drain tube is bent down at its ends so that it 70 acts as a siphon to drain all the water from the space 7.

What I claim is:—

1. A flushing or like tank composed of sheet metal having its front and end walls 75 formed from a single sheet and the bottom and rear wall formed from another sheet bent to shape, said sheets being joined at the bottom and the rear vertical corners.

2. A flushing or like tank composed of 80 metal having its front and end walls formed from a single sheet bent to shape and the rear wall and bottom formed from another sheet bent to shape, said sheets being welded together at the bottom and rear vertical corners. 85

3. A flushing or like tank composed of metal having its front and end walls formed from a single sheet bent to shape and having the bottom and back welded to the sheets 90 forming the front and end walls.

4. A flushing or like tank composed of sheet metal and having double front and end walls with an air space therebetween and having a single sheet rear wall and bottom 95 united to the sheets forming the inner and outer front and end walls, the inner front and end walls being corrugated.

5. A flushing or like tank composed of sheet metal having double front and end 100 walls with an air space therebetween and having a single rear wall and bottom welded to the sheets forming the inner and outer front and end walls.

6. A flushing or like tank having double 105 front and end walls composed of substantially parallel inner and outer walls or webs with an air space therebetween, and a rear wall and bottom of single thickness.

7. A flushing or like tank having double 110 front and end walls composed of outer and inner walls or webs with an air space therebetween, and a rear wall and bottom of single thickness, and a non-heat conducting mat covering said bottom. 115

8. A flushing or like tank formed from sheets joined by welding, the joints being in flat portions of the sheets.

9. A flushing or like tank composed of sheet metal, the sheet forming the front and 110 end walls having its bottom and rear edges turned inwardly, and the bottom and back being welded to said turned edges.

10. A flushing or like tank composed of sheet metal and having double front and 125 end walls and a single rear wall and bottom, the sheet forming the outer front and end walls having its bottom and rear edges turned inwardly to meet the edges of the inner wall and of the rear wall and bottom, 130

whereby a single joint unites all of said parts.

11. A sheet metal tank composed of three sheets, one forming outer front and end walls, and another forming inner front and end walls and the third forming the rear wall and bottom, the outer front and end wall sheet having its bottom and rear edges turned inwardly and meeting the edges of the inner wall and of the rear wall and bottom, the meeting edges of said three sheets being united by a single welded sheet.

12. A sheet metal flushing or like tank having double walls spaced apart, the sheet forming the outer wall having its edges turned inwardly and meeting the edges of the sheet forming the inner wall, and a bottom welded to the meeting edges of said inner and outer sheets.

13. A sheet metal tank provided with a cover, screws or like members extending through the rear wall of the tank for securing the same to a suitable base, and threaded rods extending upwardly from said screws through holes in the cover and arranged to receive nuts on their upper ends.

14. A sheet metal tank provided with a cover, bosses in said tank, rods threaded into said bosses and having threaded upper ends

projecting through holes in the cover, and nuts on said rods outside the cover.

15. A flushing or like tank composed of sheet metal, the sheet forming the front and end walls having its bottom edges swelled outwardly and turned inwardly and its rear edges turned inwardly, the bottom and back being welded to said inturned edges.

16. A flushing or like tank composed of sheet metal, the sheet forming the front and end walls having the top thereof provided with a strengthening bead and the bottom edges thereof swelled outwardly and turned inwardly and the rear edges thereof turned inwardly, and the bottom and back being welded to said inturned edges.

17. A flushing or like tank composed of sheet metal, and comprising a sheet bent to form the front and end walls and a bottom welded to the lower edges of the end walls, and a rear wall welded to the rear vertical edges of the end walls.

In testimony whereof, I have hereunto set my hand.

GEORGE H. BAILEY.
